UNITED STATES PATENT OFFICE.

PHILIPP WEICKEL, OF COBLENZ, GERMANY.

BOTTLE STOPPER WITH DRIP PIPETTE SECURED THERETO AND EXTENDING INTO THE BOTTLE, AND AIR ADMISSION.

Application filed June 25, 1928, Serial No. 288,147, and in Germany June 29, 1927.

This invention relates to a bottle closing device for drop glasses and like bottles.

The novel feature forming the subject matter of this invention consists in the admission 5 of air to the upper opening of the pipette by means of a channel bent at an angle and ending in the side of the stopper so that the channel is closed by inserting the stopper into the bottle neck.

10 The upper edge of the pipette may be enlarged or provided with a circumferential bead for detachably securing the pipette in the stopper. The closing stopper is preferably made entirely from rubber and of such 15 a form that the upper cylindrical portion extending into the neck of the bottle has a somewhat larger diameter than the lower portion, thus enabling the stopper to be tightly wedged into the neck of the receptacle, in an 20 unyielding manner like a wad. The lower, somewhat thinner portion of the stopper ensures the central introduction into the neck of the bottle. To facilitate the complete 25 emptying of the bottle the neck can be preferably arranged on the bottle inclined at an angle so that the lower end of the pipette can withdraw even the last drops of the contents. In this latter form of construction, the bottle 30 is preferably made with a flattened portion designed to receive a label and to facilitate the handling.

Several embodiments of the invention are illustrated, by way of example, in the accompanying drawing of which

35 Fig. 1 shows a drop-glass with drip arrangement.

Fig. 2 is a longitudinal section.

Fig. 3 shows in side elevation the stopper alone.

40 Fig. 4 is a longitudinal section of Fig. 3.

Fig. 5 shows in elevation a drop-glass with inclined neck.

Fig. 6 is a cross section through Fig. 5.

The pipette *a* is secured at the upper end in the stopper *b* by means of a head-shaped enlargement so that the mouth of the pipette *a* joins the channel *c* in the stopper *b*.

45 The pipette is preferably held in the stopper *b* somewhat elastically by the head *h*. After removing the stopper *b*, the air inlet orifice *c* is uncovered so that the atmospheric air exerts a pressure on the liquid contained in the pipette *a*, which under the pressure of the air flows out of the lower open end of the 50 pipette. The stopper *b* can be made of rub-

ber, cork, glass or other suitable material and fits in the neck of the glass *d*.

The stopper *b* is preferably made entirely of rubber and of such a shape that the upper portion *f* extending into the neck of the container is somewhat thicker than the lower portion *g* in order to obtain a cylindrical portion or body of suitable larger diameter than that of the lower portion. The lower narrower portion *g* of the stopper facilitates its being introduced centrally and the thicker cylindrical portion *f* enables the whole stopper to be tightly wedged into the neck of the bottle *d*.

The lower end *e* of the drip pipette is made 70 in the form of a capillary tube to ensure accurate, automatic dripping. So as to enable the contents of the receptacle to be entirely withdrawn with the aid of the pipette, the neck *k* of the bottle *d* can be arranged in 75 inclined at an angle, as shown in Fig. 5, so that the lower end of the pipette *a* can take up even the last drop. In the latter form of construction, the bottle can be advantageously provided with a flattened portion *l* designed 80 for a label and to facilitate handling in various instances. The bottle can, for example, be safely laid down on the flattened portion *i*.

I claim:—

1. A drop-stopper for containers comprising 85 an air admission channel bent at right angles so that the end of the horizontal arm of said channel is in the side wall of the stopper, and a pipette inserted into the lower end of the vertical arm of said channel so that 90 the air admission to said pipette is shut off when the stopper is in the bottle neck.

2. A drop-stopper as specified in claim 1, in which the pipette has a bead-like enlargement 95 at the upper end by means of which it is securely held in the channel of the stopper.

3. A stopper as specified in claim 1, in which the upper portion of the cylindrical stopper is of larger diameter than the lower portion of the same.

4. A bottle for a drop stopper as specified in claim 1 in which the neck is inclined at an angle on the bottle body.

5. A bottle for a drop stopper as specified in claim 1 having a flattened portion 105 designed to receive a label and to facilitate handling of the bottle.

In testimony wherof I affix my signature.

PHILIPP WEICKEL.
